United States Patent Office.

J. H. COLE, OF MILBURY, MASSACHUSETTS.

Letters Patent No. 77,170, dated April 28, 1868.

IMPROVED DIES FOR MAKING THIMBLES AND FERRULES.

The Schedule referred to in these Letters Patent and making part of the same.

KNOW ALL MEN BY THESE PRESENTS:

That I, J. H. COLE, of Milbury, county of Worcester, and Commonwealth of Massachusetts, have invented a Die and Plunger for Making Ferrules or Thimbles of cold wrought iron, which I believe has never before been done, to be used on drawing-knife or shave-handles, or for such other purposes as they may be applied.

By this improvement I am enabled to make ferrules of cold wrought iron much cheaper, more perfect, and much faster than it can be done by heating the iron, thereby saving expense of coal and much labor, and also making less imperfect ones.

This process of making ferrules of cold wrought iron has long been sought, but without success until now. It is only by this peculiar formation of the die and plunger that the desired result can be reached. The die and plunger must be made so as to conform to and give a gradual bearing and stretch to the iron, as it is carried or forced down the die, or it will crack or curl before receiving its proper form.

The peculiar formation of this die and plunger is such that the ferrule or thimble is formed by one impression or stroke of the press, and as fast as any one can place the disk of iron on the die; and I do hereby declare that the following is a full, clear, and exact description of the same, reference being had to the accompanying drawings, forming a part of this specification; and to enable those skilled in the art to which my invention belongs to make and use the same, I will proceed to describe it. In the drawing—

Figure 1 represents a perspective view of a die and plunger for making ferrules or thimbles—A the die, and B the plunger.

Figure 2 represents a sectional view of the die A and plunger B, the die A with a groove at the top to receive the disk of iron, from which groove commences the line of curvatures, increasing in degree to correspond with the stretch of the disk of iron, as the plunger B, with its co-acting surfaces, takes it to its final form.

C represents a perspective view of a ferrule or thimble, as formed by the co-acting surfaces of the die and plunger A and B.

Having described my die, plunger, and ferrule, I claim—

Jointly, the die and plunger A and B, the co-acting surfaces of which have the configuration herein described and shown, for the manufacture of ferrules and thimbles from disks of cold wrought iron, in the manner hereinbefore set forth.

Worcester, September 20, A. D. 1867.

J. H. COLE.
